(57) **CLAIM**

The ornamental design for a flag pole, as shown and described.

DESCRIPTION

FIG. 1 is a perspective view of the flag pole.

FIG. 2 is a front view thereof.

FIG. 3 is a back view thereof.

FIG. 4 is a right side view thereof.

FIG. 5 is a left side view thereof.

FIG. 6 is a top view of thereof.

FIG. 7 is a bottom view of thereof.

FIG. 8 is a side view of the flagpole of FIG. 1 shown in position of use; and,

FIG. 9 is a side view of the flagpole of FIG. 1 rotated in a second position of use.

The dashed lines shown in the drawings are used to illustrate the environment and form no part of the claimed design.

1 Claim, 5 Drawing Sheets
